UNITED STATES PATENT OFFICE.

ALEX G. HUHN, OF MINNEAPOLIS, MINNESOTA, ASSIGNOR TO A. HUHN MANUFACTURING COMPANY, OF MINNEAPOLIS, MINNESOTA, A CORPORATION.

DRIER.

Application filed May 31, 1919, Serial No. 300,813. Renewed February 1, 1923.

To all whom it may concern:

Be it known that I, ALEX G. HUHN, a citizen of the United States, residing at Minneapolis, in the county of Hennepin and 5 State of Minnesota, have invented certain new and useful Improvements in Driers, of which the following is a specification.

My invention relates to driers for various forms of material and particularly material 10 which might have a tendency to cling to hot surfaces and become scorched or impaired thereby. It is an object of my invention to construct a drier which shall use in the largest measure the heat elements applied to the drier without injury to the product and which shall effect drying of the 15 product with great discharge and high efficiency.

The full objects of my invention will 20 appear in connection with the detailed description thereof and are particularly pointed out in the claims.

In the drawings illustrating the application 25 of my invention in one form,—

Fig. 1 is a longitudinal sectional view of 30 the invention taken on line 1—1 of Fig. 2. Fig. 2 is a transverse sectional view taken on the line 2—2 of Fig. 2. Fig. 3 is a transverse sectional view taken on the line 3—3 of Fig. 1.

The device embodies a frame consisting 35 of a front casting 10 and rear casting 11 secured together by tie rods 12, 13 and 14, said tie rods being formed preferably as shown by the interior bolt members 15 and surrounding sleeves, or pipes, as clearly shown in Fig 3. The front lugs 16 and rear lugs 17 support the frame. The rear lugs 17 are provided with flanges 18 which, by 40 means of bolts 19 engaging a pedestal 20, enable the frame to be adjusted at a desired angle to cause the parts to slope from the rear to the front.

The front member has a main wall 21 45 provided with a circular opening 22 and bolted upon the main wall 21 is a drum member 23 having therein two chambers 24 and 25. A multiplicity of large pipes 26 are set in the inner wall of the chamber 25 opening directly into said chamber, and a corresponding number of smaller pipes 28 pass through the intermediate wall 29 which divides chambers 24 and 25. These smaller pipes extend within the large pipes 26 and open at one end into chamber 24 and at the

other end within the pipes 26, which pipes are closed by caps 30. A heating medium, such as steam or liquid oil, is admitted to chamber 24 through a pipe 31, from whence it passes through the small pipes 28 to the 60 ends of the large pipes 26 and back through the large pipes 26 into chamber 25 from which said heating medium is withdrawn by means of pipe 32 communicating with chamber 25. It will be seen that all of the pipes are 65 thus supported at their forward ends upon the drum 23. The cylinder 33 rotatably supported by rollers 34 at its rear end and rollers 35 at its front end, these rollers being rotatably mounted in lugs 17 and 16 respectively. A pinion 36 meshes with an annular spur gear 37 secured around the front end of the cylinder. The pinion 36 is keyed upon a shaft 38 which is journaled in one of the members 16. Also secured to the shaft 38 70 is a pulley 39 adapted to be driven by a belt 40. The interior of the cylinder 33 is provided with a plurality of flights 41 and a smaller cylinder 42 is concentrically mounted within the cylinder 33 and held in 75 place by brace rods 43 secured to the two cylinders. The exterior of the cylinder 42 is provided with a plurality of flights 44 which cooperate with the flights 41 to lift the grain or other material as it is fed into 80 the annular space between the cylinders by a screw conveyor 45 which delivers into this space at the rear of the apparatus. Immediately after it has been dried by passing through the apparatus it is discharged at 85 the front into a spout 46 connected to the casting 10. To the inner surface of the rear casting 11 is secured a drum member 47 which carries a flange member 48 within which the rear end of the inner cylinder 42 rotates. Some of the pipes 26 are sufficiently long to extend into the upper portion of the space within the drum 47 and a pipe 48' leads into this space to provide for the entrance of air which is drawn through 100 the inner cylinder over the pipes and caused to be deflected alternately, upwardly and downwardly by upper baffle plates 49 and lower baffle plates 50 arranged in staggered relation, with their ends extending slightly beyond the axial line of the inner cylinder, as indicated in Fig. 2. The air which is drawn through the inner cylinder in the manner just described passes out of the forward end thereof into the annular space 105 110

between the cylinders and passes back through the material which is being repeatedly lifted by the blades, as previously stated, and allowed to drop over the inner cylinder. The current of air through the apparatus is produced by a fan connected with a casing 51 in communication with the annular space between the cylinders at the rear.

- 10 The advantages of my improved drier are quite clearly pointed out in connection with the detailed description thereof. Any degree of heat which is desired may be obtained and yet the material operated upon 15 will not be scorched or impaired, or even discolored. The heating pipes being entirely within the inner drum, the direct radiation of heat from such pipes is transmitted to the walls of said inner drum, 20 which in turn transmit the heat to the annular chamber which constitutes the drying area. For this reason there is no loss of heat and the air admitted through the inlet opening 48' becomes rapidly and uniformly 25 heated. This air passes first through the discharge stream of material within the heated chamber leading to the discharge passageway 46. The air at that time is the hottest and the driest, and therefore removes 30 from the discharging material the last desired amounts of moisture. This air is constrained to pass through the annular drying chamber in a uniform heated stream and is at all times in contact with the double 35 streams of falling material, that is the material falling from the flights in the outer drum upon the inner drum at the upper part of the annular drying chamber, and material falling from flights on the inner 40 drum to the outer drum in the lower part of the annular drying chamber. There will also be more or less falling of material at the sides, so that substantially the entire annular chamber will be filled with falling 45 material subjected to the draft of heated air. It thus follows that for the actual space within the drum a maximum amount of drying is effected. The air inlet pipe 48' is preferably provided with a damper mechanism 50 whereby the supply of air to the interior is accurately regulated. The material instead of being fed in by means of a screw through the inlet pipe 45 may be fed by any suitable means. The means herein 55 shown is, however, of peculiar advantage where the material is moist or sticky or agglomerated, as it insures the constant feed and insures the breaking up of the material before it reaches the heating mechanism. 60 The arrangement for mounting the pipes within the drums it will be seen is very simple and enables the pipes readily to be removed if desired for repair or other reasons. Furthermore, the baffle plates 49 and 65 50 have the effect of causing the air within

the cylinder 42 to move alternately in transverse direction across the lengths of the pipes and against the walls of cylinder 42, thus insuring maximum heating effect upon the air and also upon the wall of cylinder 70 42. Thus a much more efficient heating effect upon the air can be obtained than if it traveled in a direct line longitudinally of the pipes.

I claim:

1. A drier comprising a casing which constitutes a drying chamber, heating means surrounded by said chamber, means for causing air to pass over said heating means and through said chamber, and means for feeding material to be treated into said chamber.

2. A drier comprising a rotating member having an annular drying chamber, heating means surrounded by said annular chamber, 85 means for causing air to pass over said heating means and through the annular chamber, and means for feeding material to be treated into the annular chamber.

3. A drier comprising a rotating member having an annular chamber and a central chamber surrounded by said annular chamber, a battery of heating pipes in said central chamber, means for admitting atmospheric air to the central chamber only at 90 one end and for admitting air from said central chamber at its other end to the annular chamber, means for causing the air to move through said chambers and be discharged to atmosphere, and means for feeding the material to be treated into the annular chamber.

4. A drier comprising a rotating member having an annular chamber and a central chamber surrounded by said annular chamber, a battery of heating pipes in said central chamber, means for causing a heating medium to circulate through all the pipes of said battery, means for admitting atmospheric air to the central chamber only at 95 one end and for admitting air from said central chamber at its other end to the annular chamber, means for causing the air to move through said chambers and be discharged to atmosphere, and means for feeding the material to be treated into the annular chamber.

5. A drier comprising a rotating member having an annular chamber, means for generating heat surrounded by said annular chamber, means for feeding material to be treated into said annular chamber, means holding said annular chamber at an angle to the horizontal whereby the material is caused to gravitate through the chamber as the member is rotated, and means for receiving material from the annular chamber and discharging it from the drier.

6. A drier comprising a pair of concentric drums held in fixed spaced relation so

as to provide an annular chamber between said drums, means for rotating said drums, heating means within the inner drum, means for causing air to pass through the inner drum and over said heating means and thereafter through the annular chamber, and means for feeding material into the annular chamber.

7. A drier comprising a pair of concentric drums held in fixed spaced relation so as to provide an annular chamber between said drums, means for rotating said drums, means sealing said annular chamber from the interior of the inner drum at one end, means opening the annular chamber to the interior of the inner drum at the other end, means for admitting air to the inner drum at said sealed end, means for drawing air from the annular chamber at said sealed end, heating means within the inner chamber, and means for feeding material into the annular chamber at said sealed end and for withdrawing said material from the annular chamber at the other end.

8. A drier comprising a rotating member having an annular drying chamber and an interior heating chamber, a battery of pipes in said heating chamber, means for ad-

mitting air to said heating chamber and drawing it through the same and thereafter through the annular chamber, means in the heating chamber for causing the air to move alternately from one side to the other of the heating chamber transversely across the pipes, and means for feeding material to be treated into the annular chamber.

9. A drier comprising a rotating member having an annular drying chamber and an interior heating chamber, a battery of pipes in said heating chamber, means for admitting air to said heating chamber and drawing it through the same and thereafter through the annular chamber, a multiplicity of baffle plates in the heating chamber extending part way across the same and through which the pipes extend, said plates being in staggered relation to cause the air within the heating chamber to move alternately from one side of the heating chamber to the other transversely across the pipes, and means for feeding material to be treated into the annular chamber.

In testimony whereof I hereunto affix my signature.

ALEX G. HUHN.
